[57] CLAIM

The ornamental design for an air scoop for a toilet ventilator, as shown and described.

DESCRIPTION

FIG. 1 is a bottom view of an air scoop for a toilet ventilator showing our new design;

FIG. 2 is a top plan view thereof;

FIG. 3 is a side view thereof;

FIG. 4 is a side view of FIG. 1, taken from the opposite side thereof;

FIG. 5 is an end view thereof;

FIG. 6 is an end view end thereof;

FIG. 7 is a perspective view of the air scoop from the outlet end thereof; and,

FIG. 8 is a perspective view of the inlet end thereof.
